ORIFICE RING USED IN GLASS MANUFACTURING MACHINERY AND THE LIKE

Robert S. Bracken, Vineland, N.J., assignor to Maul Bros. Inc., Millville, N.J., a corporation of New Jersey

Filed Aug. 14, 1967, Ser. No. 8,245

Term of patent 14 years

(Cl. D55—1)

FIG. 1

FIG. 2

FIG. 3

FIG. 4

FIGURE 1 is a top perspective view showing my new design;

FIGURE 2 is a bottom perspective view thereof;

FIGURE 3 is a front elevation view thereof; and

FIGURE 4 is a side elevation view thereof.

The rear elevation view is identical with the front elevation view. The side elevation view, not shown, is identical with the side down.

I claim:

The ornamental design for an orifice ring used in glass manufacturing machinery and the like, substantially as shown and described.
